[57] **CLAIM**

The ornamental design of a housing for a telephone set, substantially as shown and described.

DESCRIPTION

FIG. 1 is a front elevation of a housing for a telephone set embodying our new design;
FIG. 2 is a side elevation thereof;
FIG. 3 is a rear elevation thereof;
FIG. 4 is a top plan view thereof;
FIG. 5 is a top plan view of the base shown separately for clarity of illustration;
FIG. 6 is a bottom plan view of the handset;
FIG. 7 is a side elevation thereof; and
FIG. 8 is a front elevation thereof.

FIG. 1

FIG. 2

FIG. 3

FIG. 4

FIG. 5

FIG. 6

FIG. 7

FIG. 8
